UNITED STATES PATENT OFFICE.

EVERETT R. HOWARD, OF AURORA, ILLINOIS, ASSIGNOR OF ONE-HALF TO
ROSWELL W. GATES, OF SAME PLACE.

SMOKE AND GAS CONSUMING FURNACE.

SPECIFICATION forming part of Letters Patent No. 341,008, dated May 4, 1886.

Application filed January 29, 1886. Serial No. 190,155. (No model.)

To all whom it may concern:

Be it known that I, EVERETT R. HOWARD, a citizen of the United States of America, residing at Aurora, in the county of Kane and State of Illinois, have invented certain new and useful Improvements in Smoke and Gas Consuming Furnaces, of which the following is a specification, reference being had therein to the accompanying drawings.

10 The nature of my invention relates to the construction of boiler-furnaces, with the object in view of consuming the smoke and gases generated from the fuel upon the grate; and it consists of the novel devices and combinations of devices hereinafter described and specifically claimed.

In the accompanying drawings, Figure 1 represents a longitudinal vertical section of the furnace, and Fig. 2 a transverse vertical section on line 2 2 in Fig. 1.

Corresponding letters in both the figures of the drawings designate like parts.

A denotes the boiler, that may be of any usual construction, with flues for the return-draft. B is the boiler-front, C the grate, and D the ash-pit.

E is the bridge-wall extending from the rear end of the grate to near the rear end of the boiler and being inclined toward the rear, that by degrees the gas and smoke passage between such boiler and bridge-wall will be increased toward the rear. The rear end e of the bridge-wall E slopes down on an angle of about forty-five degrees, and from the extreme rear end 35 of boiler A is built a pending wall, F, supported by an arch, f, and forming a partition or diaphragm, only leaving between such arch f and the base of the furnace a shallow opening, g, for providing communication from the 40 gas-channel under the boiler to smoke-chamber G, that again communicates with the return-flues projected through such boiler. A door, h, provides admission to or inspection of such smoke-chamber G.

45 Either longitudinally or transversely I build through the base of the furnace a channel or flue, H, with its exteriorly-projecting ends communicating with the atmospheric air, which openings may be arranged to be closed 50 or regulated by suitable valves. This chan-

nel H has one or more branches, i, leading into opening g, vertically below arch f. The products of combustion, after passing through the flues in the boiler, are carried off through breeching I.

55

J is the blow-off pipe, provided with a cock in the usual manner.

A fire having been started on grate C, the incandescent coal is shifted toward the rear against the bridge-wall and fresh fuel is 60 shoveled upon the front part of the grate.

The fuel-door and ash-pit door now being closed, to admit but very little air to the burning fuel, the gases and smoke, principally consisting of hydrocarbon gases that are gen- 65

erated from such fuel during the coking process, will first pass over the incandescent coal, to be highly heated thereby, and will thence pass over the bridge-wall toward the rear end thereof, where these gases are interposed on 70

their direct course by the wall F. The gases in condition for combustion occupying more space than the products of combustion, such com- 75

bustion diminishes their volume and thereby creates a partial vacuum, and on that account, 75

after combustion once has commenced in my furnace, such vacuum will produce a continuous suction of air from channel H through branch i, which air will be drawn into the space between boiler A and bridge-wall E; 80

but being cold, and therefore heavier than the gases, the air is not in condition to intermin- 85

gle, but will pass below the gases toward the grate in a counter-current until in its course it is heated to the required degree, when, 85

with a whirl, such air will mix with the gases and its oxygen will unite by an explosion, thereby chemically uniting with the hydrocarbon and forming into carbonic acid and vapor of water, the principal products of combus- 90

tion, that now will pass off through opening 95

g into the smoke-chamber and thence through the return-flues in the boiler to the breeching and chimney. Part of the gases may pass through opening g into the smoke-chamber 95

unconsumed, which, however, will there re-

ceive an additional supply of oxygen from the air-supply through channel H and branch i, to

be readily burned before reaching the return- 100

flues in the boiler. In this manner no gases

or smoke can leave the several combustion-chambers without utilizing fully their combustible qualities.

The products of combustion while passing through the return-flues in the boiler will give up therein the greater portion of their heat, and because such products of combustion, mainly consisting of carbonic-acid gas and of vapor of water, and carrying no substance that may clog the surface of such return-flues and thereby diminish their heat-conducting capacity, a great saving of fuel is the result of my arrangement.

What I claim is—

1. In a boiler-furnace, the combination, with the grate, bridge-wall, and smoke-chamber, of a pending rear wall providing the only communication to such smoke-chamber from under such wall, and of an air-channel through

the base of such furnace, communicating with the gas-duct through an opening vertically below and opposite to such pending wall, substantially as and for the purpose set forth.

2. In a boiler-furnace, the combination, with the grate, bridge-wall, and smoke-chamber, of the pending rear wall, F, with passage g thereunder, and of channel H through the base of such furnace and communicating with passage g through opening i, that is vertically below and on a line with such pending wall, substantially as and for the purpose set forth.

In testimony whereof I affix my signature in presence of two witnesses.

EVERETT R. HOWARD.
